(57) **CLAIM**

The ornamental design for a seashell holder for rings and things, as shown and described.

DESCRIPTION

FIG. 1 is a top isometric view of a first embodiment of holder according to the invention.

FIG. 2 is a top view of the holder of FIG. 1;

FIG. 3 is a front view of the holder of FIG. 1;

FIG. 4 is a side view of the holder of FIG. 1;

FIG. 5 is a back view of the holder of FIG. 1;

FIG. 6 is a bottom view of the holder of FIG. 1;

FIG. 7 is a top view of a second embodiment of holder according to the invention;

FIG. 8 is a front view of the holder of FIG. 7;

FIG. 9 is a side view of the holder of FIG. 7;

FIG. 10 is a back view of the holder of FIG. 7;

FIG. 11 is a bottom view of the holder of FIG. 7;

FIG. 12 is a top view of a third embodiment of holder according to the invention;

FIG. 13 is a front view of the holder of FIG. 12;

FIG. 14 is a side view of the holder of FIG. 12;

FIG. 15 is a back view of the holder of FIG. 12; and,

FIG. 16 is a bottom view of the holder of FIG. 12.

The stippling shown in FIGS. 3-6, 8-11 and 13-16 represents a contrasting appearance.

1 Claim, 13 Drawing Sheets
